(57) **CLAIM**

The ornamental design for trousers, as shown and described.

DESCRIPTION

FIG. 1 is a front perspective view of trousers showing my new design, with drawstrings about the waist and edge of the pant legs in a uncinched state;

FIG. 2 is a rear perspective view of the trousers shown in FIG. 1;

FIG. 3 is a front perspective view of the trousers shown in FIG. 1 with the drawstrings about the waist and edge of the pant legs in a cinched state; and,

FIG. 4 is a front perspective view of the trousers shown in FIG. 1 with the drawstrings about the waist and edge of the pant legs in a cinched state, and the pant legs gathered towards the waist.

The broken lines in the drawing are understood to represent stitching.
